UNITED STATES PATENT OFFICE.

LEW B. EVANS, OF MARIETTA, OHIO.

ROAD GRADER.

Application filed November 18, 1921. Serial No. 516,181.

To all whom it may concern:

Be it known that I, LEW B. EVANS, a citizen of the United States of America, and resident of Marietta, in the county of Washington and State of Ohio, have invented certain new and useful Improvements in Road Graders, of which the following is a specification.

This invention relates to road graders and scrapers, and particularly to novel means for controlling the positions of the scrapers by manually operated means within convenient reach of a driver; the said invention furthermore having novel means by which the scrapers may be swung inwardly or away from the center of the road and held at different positions of adjustment by means which are strong and durable that will prove efficient and satisfactory in use.

A further object of this invention is to provide novel means for adjusting the scrapers vertically, both at their pivotal ends and at their free ends, in order that their action will be uniform from end to end.

A still further object of this invention is to produce a road working machine of the character indicated, having but two ground or traction wheels in which a rigid frame is mounted on the said wheels, the said machine being supported in front through the connection of a tongue with a tractor or the like, by which the road worker is drawn.

A still further object of this invention is to produce a road worker of the character indicated having rearwardly extending road crowning blades manually operated and adapted to be held at different positions of adjustment.

With the foregoing and other objects in view, the invention consists in the details of construction, and in the arrangement and combination of parts to be hereinafter more fully set forth and claimed.

In describing the invention in detail, reference will be had to the accompanying drawings forming part of this application, wherein like characters denote corresponding parts in the several views, and in which—

Figure 1 illustrates a plan view of a road grader embodying the invention;

Figure 2 illustrates a side elevation thereof;

Figure 3 illustrates a rear elevation;

Figure 4 illustrates a perspective view of

a fragment of one of the blades associated with its mounting and parts of the frame;

Figure 5 illustrates a horizontal section view on the line 5—5 of Fig. 4;

Figure 6 illustrates a sectional view of the device on a line corresponding with the line 6—6 of Fig. 5;

Figure 7 illustrates an enlarged detail view of a hand wheel and parts associated with it; and

Figure 8 illustrates a detail view of a scraper blade adjusting mechanism.

In these drawings 5 denotes a rear axle on which the wheels 6 are mounted, the said axle extending through the wheels, and each end forming a support for the outer end of a yoke 7, whereas the inner end of the yoke is supported on the axle on the opposite side of the wheel. Each yoke has a bifurcated block 8 secured on its upper surface 75 and the furcation of each block has a pivot 9 extending through it, on which a bell crank lever 10 is oscillatably mounted.

In the further description of this invention, attention is directed to the fact that in this machine the parts are duplicated on each side of the transverse center, and therefore, a description of the parts on one side thereof will act as a disclosure of the companion parts on the opposite side, so that it is thought unnecessary to duplicate the description for the two sides.

The bell crank 10 has one arm extending upwardly and provided with a hook 11 which enters an aperture 12 in an arm 13 which projects from a segmental worm wheel 14, the said worm wheel being rotatable or partially rotatable on the pivot 15 of the frame, which comprises in part, a standard 16 rising from a beam 17 and strengthened by a brace 18. Any suitable frame structure of sufficient strength will, of course, answer the purpose of this invention. Braces 20 connecting the beams 17 and 19 also aid in strengthening the structure and aid in producing a rigid frame. Preferably, a tubular tongue 21 extends outwardly from the frame and terminates in a coupling 22, such as a hook or the like, by which it may be attached to a tractor or a draft rigging of a motor by which the road worker is to be drawn.

The arm 23 of the bell crank lever 10 has its end extending into a socket 24 of a plate 25 attached to the standard 16, and by the

- manipulation of the bell crank lever, the frame is elevated or lowered with respect to the axle 5, the bell crank lever forming the support for the frame at one side of the machine, and there being like supporting means at the opposite side thereof. A worm 26 is suitably journaled in the frame, and is in mesh with a worm wheel 14, the said worm 26 being mounted on a shaft with the beveled 10 pinion 27, which beveled pinion 27 is engaged by a beveled pinion 28 on a shaft 29 by which the worm may be rotated in either direction to operate the worm wheel and impart movement to the frame, as indicated.
- 15 A hand wheel 30 on the shaft may be manipulated by an operator occupying the seat 31 and hence the frame may be elevated or lowered to regulate the support of the rear end of the scraper, as will presently appear.
- 20 The shaft 29 is rotatable in a bearing 32 on a beam 33 which is elevated with respect to the lower beams of the frame, and there is a beam 34 in front of the first mentioned elevated beam which constitutes a support 25 for the bearing 35 of a shaft 36 having a hand wheel 37. A vertically disposed shaft 38 is journaled in the frame and it has a worm 39 thereon and a beveled pinion 40 engaged by a pinion 41 on the shaft 36. By 30 means of the hand wheel 37, which as before stated is also provided on the shaft 36, the worm 39 may be rotated in opposite directions, according to the direction of rotation of the hand wheel. A bracket 43 extends 35 outwardly from the shaft 38, and it forms a support for a segmental worm 44 having an arm 45 projecting outwardly therefrom, the said worm being engaged by the worm wheel. The arm 45 has a link 46 loosely 40 connected to it and the opposite end of the link is connected to the scraper blade 47 or rather to the brace 48 thereof in order that the scraper blade may be raised and lowered, according to the oscillation of the arm 45. The scraper blade has its inner end rotatably or pivotally mounted on a bracket 49 depending from the frame, and hence, as the frame is raised or lowered, the rear end of the blade is raised or lowered, where- 45 as the front end of the blade is controlled by the position of the arm 45.
- 50 Braces 50 connect the beam 34 with the tongue through the coupling plate 51, and the said coupling plate has an aperture 52 55 therein to receive a hook of one of the braces 50. The brace 50 is preferably sectional and provided with a turn buckle 53 by which tension may be diminished or increased, according to the requirements.
- 60 The scraper on each side is moved inwardly and held at different positions of adjustment by a beam 53' which is oscillatably mounted on a pivot 54 carried by the blade, and this beam has its outer end provided with a coupling 55 for a flexible element 56 which may

be in the nature of a cable operating over a sheave pulley 57 which is connected to the tongue by the fixture 58, the said cable extending rearwardly and being wound on a sheave 59. The sheave has a ratchet wheel 60 associated with it, which is intended to be engaged by a dog 61 whereby the parts will be held at different positions of adjustment to retain the tension on the cable. The ratchet wheel is engaged by a pinion 60^a 75 on a shaft 60^b and a hand wheel 62 is mounted on the shaft 60^b for operating the said shaft. As the hand wheel 62 is within convenient reach of an operator, the scraper blades may be allowed to swing outwardly 80 to a greater or less extent, or they may be drawn quite close to the center, according to the requirements, as the operation proceeds.

85 There is a curved blade 63 which is operated by a segment 64 and a worm 65 by which the blade can be raised or lowered. The bracket 49 which is connected to the blade 47 is oscillatable on a pin 66 extending through a post 67, which post is supported by suitable anchorages on the frame, and each blade has ears 68 secured to the bracket by pivots 69, so that the blade may be tilted to change its angle with relation to the surface being treated. The post 67 has a clip 70 to which a link 71 is pivoted, and each blade has a bracket 72 adjustably connected to the link as at 73, it being shown that the link has apertures to permit the coupling 90 to be secured at different positions to hold 100 its different positions of adjustment.

The rear scraper blade 63 has its ends adjustably secured on a bracket 74 which is also carried by the post 67, but the bracket is rigidly secured with relation to the post. The scraper blade 63 has an apertured member 75 at each end through which the pivot 76 may extend by which the scraper 63 is connected to the apertured portion 77 of the said bracket 74, and of course the scraper 63 may oscillate to increase or diminish the height of the scraper from the surface being treated, through means of the worm and segment 64, the said segment being connected to the blade by a link 78.

110 115 The wheels 62 are each held at different positions of adjustment by a spring actuated detent 79 oscillatable on a pivot 80, the said detent being integral with a pedal 81 which may be pressed to release the detent 120 from the periphery of the wheel.

I claim:

125 In a road scraper, a frame, traction wheels separate from the frame, pivotally mounted means supported by the traction wheels, means for connecting the pivotally supported means to the frame whereby the frame is elevated or lowered, worm and gear mechanism for actuating the pivotally mounted supporting means, scraper blades having

their rear ends pivotally mounted on the frame, links connected to the said blades, the blade operating mechanism being arranged in pairs each comprising an arm, a bracket on which the arm is oscillatably mounted, a segmental worm forming a part of each arm, a shaft on which the bracket is mounted, a worm wheel on the shaft for engaging the worm of the arm, means for rotating the shaft in opposite directions for oscillating the arm, and means for moving the blades transversely and for holding them in different positions of adjustment.

LEW B. EVANS.
